PORTABLE MILKING MACHINE

Benjamin H. Anderson, Madison, Wis.

Application December 15, 1939, Serial No. 309,449

6 Claims. (Cl. 31—73)

This invention relates to portable milking machines.

One of the objects of this invention is to provide a portable milking machine which is simple in construction and easy to operate.

Another object of this invention is to provide means for centering the suction pump cylinders and for readily regulating or adjusting the degree of vacuum developed by the suction pumps.

Another object of this invention is to provide simple means for guiding the motion of the suction pump cylinders.

Another object of this invention is to provide means for lubricating the piston guiding means.

A further object of this invention is to provide a compact portable milking machine in which the operating elements are enclosed and yet are readily available for inspection.

Further objects and advantages of this invention will become apparent from the following detailed description and the accompanying drawings, wherein:

Fig. 1 is a side view, partly in section and with one panel of the housing removed, of a portable milking machine embodying my invention.

Fig. 2 is a front view, partly in section and with the front panel of the housing removed, of the portable milking machine of Fig. 1.

Fig. 3 is a sectional view, at an enlarged scale, taken on line 3—3 of Fig. 2.

Fig. 4 is a detailed view of the connection between the connecting rod and the piston guide tube.

Fig. 5 is a detailed view of the driving motor supporting means.

Fig. 6 is a cross sectional view, at an enlarged scale, of the turret member.

Figs. 7, 9, and 11 are bottom views, at an enlarged scale, of valve members and associated valve or milk receiving chambers mounted in the milk container covers.

Figs. 8, 10, and 12 are sectional views of the members illustrated in Figs. 7, 9, and 11, taken on lines 8—8, 10—10, and 12—12, respectively.

Referring to the drawings, the milking machine comprises a base 1, which is preferably of cast metal, supported on wheels 2. The central portion of the base is preferably raised, as at 3, to provide a platform on which is mounted a reduction gear unit 4. Adjacent the sides of platform 3 the base is provided with wells 5. A casting or housing 6 is mounted on base 1 and comprises side panels 7 and 8, front panel 9, rear panel 10, and cover 11. The side panels are provided with removable plates 12 and 13 which may be

removed easily to provide ready access to the operating elements.

Vacuum cylinders 14 are supported from cover 11 of housing 6. The upper ends of cylinders 14 are closed by caps 15, each of which is provided with a spigot 16. The cylinders are retained in cover 11 by means of clamp 17 which is drawn tight by means of bolt 18, secured to cover 11 by means of nut 19. The cylinders are maintained in centered position by means of clamping rings 20.

Clamping rings 20 are arcuate, having their end portions 21 and 22 bent outwardly. Bracket 23 is securely mounted on front panel 9 of housing 6. End portions 21 of the clamping rings are secured to bracket 23, as by spot welding. Bearing plates 30 may be secured to the free end portions 22 of the clamping rings. Bracket 23 is provided with threaded apertures 24 adapted to receive the threaded ends 26 of studs 25. The fixed end portions 21, the free end portions 22 and bearing plates 30 are provided with apertures through which the threaded ends 26 of studs 25 may project.

25 The studs 25 are provided with an enlarged section 27 to form a shoulder 28 which bears against bearing plate 30. The studs project outwardly of housing 9 and are provided with knurled heads 29 to permit ready adjustment. 30 Bearing plates 30 may be provided with end portions 31 bent at right angles to provide means for limiting closing of the clamping rings. Coil springs 32 encompass the threaded portions 26 of the studs between end portions 21 and 22 of the clamping rings to constantly urge the clamping rings into expanded position.

It is obvious that upon drawing up studs 25 in threaded apertures 24 in brackets 23, the end portions 21 and 22 of clamping rings 20 are brought toward each other and the clamping rings are tightly drawn about cylinders 14. The clamping rings provide simple, effective means for centering the cylinders and maintaining the cylinders in centered position. The clamping rings 35 may be released easily and readily to permit removal of the cylinders through the apertures in cover 11.

Cylinders 14 are provided with diametrically opposite apertures 33 underlying clamping rings 20. Cooperation between apertures 33 and clamping rings 20 provides a simple, effective means for adjusting the degree of vacuum developed by the vacuum pumps. Upon drawing up studs 25 in threaded apertures 24 in brackets 23, clamping rings 20 are tightly drawn about cylinders 14

and thereby seal the apertures 33. Sealing the apertures 33 increases the degree of vacuum developed by the vacuum pumps. Loosening of studs 25 slightly, although the clamping rings remain effective in centering the cylinders, breaks the seal overlying apertures 33 and thereby decreases the degree of vacuum developed by the vacuum pumps. The decrease in the degree of vacuum developed is directly dependent upon the degree of opening of the apertures, which is in turn directly dependent upon the degree to which the clamping rings are opened.

Brackets 34 are mounted on the housing of gear reduction unit 4, or may be integral with the housing, as illustrated in the drawings. Oil reservoirs or cups 35 are positioned on brackets 34, both the oil cups and brackets being provided with apertures. A guide rod 36 is positioned on each of the brackets, the lower ends of the guide rods being threaded and passing through the apertures in the oil cups and the brackets. The guide rods are secured to brackets 34 by means of nuts 36a. The guide rods extend upwardly, projecting through apertures in cover 11. The upper ends of the guide rods may be secured to cover 11 by means of nuts 37. The guide rods are positioned directly behind cylinders 14.

A tubular member 38 is positioned slidably on each of the guide rods 36. A bracket 39, having a forwardly projecting arm 41, is securely fastened to tubular member 38, being spaced from the lower end of the tubular member an amount sufficient to allow the lower end of the tubular member to extend well into oil cup 35 when the tubular member is in its lowermost position. The lowermost end of piston rod 40 is secured to the forwardly projecting arm 41 of the bracket 39. Piston 42 is secured to the uppermost end of piston rod 40.

A collar 43 is securely fastened to the uppermost end of tubular member 38. A bearing pin 44 is integral with collar 43, or may be secured to the collar. Tubular member 38 is provided with an aperture 45, collar 43 and pin 44 are provided with a diametrical aperture 46a, for purposes to be described hereinafter. Tubular member 38 is reciprocated along guide rod 36 by connecting rod 47 which is pivotally connected to pin 44. The connecting rod 47 is in turn driven by gear reduction unit 4 through crank 48. The gear reduction unit is driven by a motor 49 through pulley 50 and belt 51.

Motor 49 is secured to platform 52 exteriorly of housing 6. In order to provide simple means for adjusting the tension in belt 51, platform 52 is preferably mounted pivotally on the rear panel 10. Flanges 53 may be provided on the panel 10 and platform 52 is pivotally secured to the flanges 53 by means of bolts 54. A pair of cooperating plates 55 and 56, each having a slot 57 and 58 serve as means for maintaining the platform in any desired position. Plates 55 and 56 may be of sheet metal and are secured to platform 52 and panel 10, respectively. The plates are maintained in any desired position by friction between the plates. The plates are tightly clamped together by means of bolts 59 which pass through the slots 57 and 58 and ring nuts 60.

A milk container 61 is supported on a platform 62 which is secured to the front panel 9. The open end of milk container 61 is provided with a cover 63. A valve member 64, the construction of which will be described hereinafter,

is positioned in an aperture in cover 63. The valve member is retained in the aperture in cover 63 by means of yoke 65, which is retained on the cover by a bolt and a cooperating ring nut 66.

5 A rod 67 is rigidly secured to front panel 9 in spaced relation thereto. A cover holding arm 68 is slidably mounted on rod 67. The bore of the aperture in the arm 68 is of such diameter as to permit the arm to be raised or lowered easily when held at substantially right angles to the axis of the rod, but is sufficiently small in diameter to prevent the free movement of the arm along the rod. Since the center of gravity of the arm is at some distance from rod 67, the downward pull of gravity is adequate to create sufficient frictional force between the rod and the edges and surfaces of the aperture to hold the rod in any position to which the arm may be raised or lowered.

10 The free end of arm 68 is preferably hook-shaped and is provided with a rubber snubber 69. Ring nut 66 is placed on the hook-shaped end of arm 68 whereby the associated container cover 63 and valve member 64 may be supported while placing a milk container 61 on platform 62. The pull of gravity of the arm 68, cover 63, valve member 64 and associated elements creates sufficient friction between the rod and the edges and surfaces of the aperture in arm 68 to retain the arm in any position to which it is moved.

15 The arm may be held in a right angle position with respect to rod 67 and may be lowered until cover 63 is positioned on milk container 61. The arm is then lowered until the snubber rests on the lower inside surface of ring nut 66. The arm may be pressed into contact with the inner surface of the ring nut. The snubber 69 exerts adequate pressure upwardly to create sufficient friction between rod 67 and arm 68 to maintain the cover in position until it is desired to remove the milk container. If it is desired to remove cover 63, the arm may be placed in a right angle position with respect to rod 67 by exerting a downward pressure on the arm to compress further the snubber. The arm may be raised whereby the cover and associated elements may be held at a position above the top of milk container 61 to permit its removal or replacement.

20 I have also found that it is not necessary to move arm 68 downwardly into contact with the ring nut when the machine is in operation since the vibration of the apparatus will be sufficient to cause the arm to walk downwardly by gravity. It is also not necessary to compress the snubber into contact with the lower inside surface of the ring nut. Nor is it necessary to support the cover from the arm. The cover may be handled as desired and the snubber may be placed in direct contact with the upper surface of the cover, if desired.

25 The cooperating substantially vertical rod 67 and arm 68 form an exceedingly simple yet reliable and very effective means for supporting cover 63 and the associated elements and for preventing accidental displacement of the cover during operation and use of the milking machine.

30 A turret 70 is mounted on support 71 which is secured rigidly to cover 11, as by welding or other suitable means. The turret comprises a pair of disc holders 72 and 73 mounted rotatably on support 71. The disc holders are identical in construction, see Fig. 6, each comprising a cup-like body 74 having its wall flared out-

wardly slightly at the open end of the body, to provide a bearing surface 75. A centrally positioned journal 76 is provided to receive bolt 77 which passes through the journals of each of the bodies and through support 71. A nut 78 is threaded on the lower end of bolt 77 to secure the disc holders to support 71. Bearings 79 and 81 are positioned to one side of the journals and are provided with openings 80 and 82, respectively. Disc holders 72 and 73 are assembled with their open ends toward each other and with surfaces 75 in contact. Supporting arms 83 and 84 are mounted slidably in openings 80 and 82, respectively.

Bolt 77 is drawn up or tightened sufficiently so that the supporting arms 83 and 84 can be moved with a slight force. The weight of the supporting arms creates sufficient friction between the bearing surfaces 75 of the disc holders to maintain the arms in any desired position into which they may be moved.

A trap 85 may be interposed between the vacuum pumps and valve members 64. The trap provides simple means by which the dairyman may quickly detect a failure in the apparatus such as will cause a flow of milk into the vacuum pumps. Trap 85 is mounted on front panel 9. The trap may comprise a transparent cup 86 and a head 87. The head is provided with two conduits 88, one of which appears in Fig. 1, and a depending rod 89 which extends through the cup. The lower end of rod 89 is threaded and receives nut 90. The cup is securely clamped between head 87 and nut 90. If desired, rubber or other washer members 91 may be positioned between the top of the cup 86 and head 87 and between the lower end of the cup and nut 90. It is to be understood that the milking machine may be operated with equal effectiveness without the trap. It is also to be understood that a trap is provided for each of the vacuum pumps.

Spigot 16 of each of the vacuum pumps is connected with one of the conduits 88 in the head 87 of its associated trap by flexible tubing 92. The remaining conduit 88 of the head 87 is connected with its associated valve member 64 by means of flexible tubing 93. Valve members 64 communicate with the milk claws 94 by means of flexible tubing 95. The milk claw 94 in turn communicates with a plurality of teat cups 97 by means of short lengths of flexible tubing 96. Flexible tubing 95 and the milk claw 94 with its cluster of teat cups may be supported by hook 98 which is secured to the end of supporting arm 83.

It is to be understood that a similar milk claw and associated elements are provided for each vacuum pump and valve member.

In Figs. 7 to 12, inclusive, I have illustrated, in detail, the construction of several embodiments of the valve members. The valve and valve chamber structure is disclosed and claimed in Patent No. 2,287,506, issued June 23, 1942.

Referring to Figs. 7 to 8, the valve member 64 comprises a valve retaining ring 100, a valve plate 101, and a valve chamber 102. The valve retaining ring comprises a tubular sleeve 103 having a reduced portion 104 forming an external shoulder 105 and an internal ledge 106. The reduced portion 104 is adapted to be positioned within opening 107 in cover 63, shoulder 105 being disposed on rim 108 which defines opening 107. A spider 109 is provided with cut-out portions 110 and with a centrally located aperture 111. The spider is preferably formed by a stamp-

ing operation and its central portion is raised as at 112. A valve plate 101 is disposed on the spider 109, the aperture 111 receiving guide pin 113. The guide pin and aperture cooperate to maintain valve plate 101 in centered position at all times. In forming raised portion 112 and aperture 111, I prefer to draw the metal to provide a bearing surface for pin 113 which is longer than the normal thickness of the spider.

10 The valve chamber 102 is preferably cylindrical and is provided with an enlarged base portion 115 which forms an external shoulder 116. The enlarged base portion 115 fits loosely within sleeve 103, being positioned on spider 109. The valve retaining ring and the valve chamber are maintained in opening 107 by means of yoke 65, the extremities of the yoke bearing upon shoulder 116 of the valve chamber. In the assembled position of the valve retaining ring and valve chamber, the spider 109 is held securely between internal ledge 106 and the lower end of the valve seat 117.

15 Air spigot 118 communicates with the interior of the valve chamber and with a source of vacuum, such as vacuum cylinder 14, illustrated in Figs. 1 and 2. Milk spigot 119 communicates with the valve chamber and with the teat cups 97 through flexible tubing.

20 In operation, on application of vacuum to air spigot 118 or on the suction stroke of the pump, the clearance between valve plate 101 and valve seat 117 is sufficiently small to permit the valve to be closed by atmospheric pressure on the underside of the valve plate. On closing of the valve, milk is drawn through the teat cups, associated milk claw, associated tubing, and milk spigot 119, and flows into valve chamber 102.

25 30 35 40 45 On the return stroke of the pump or the breaking of the vacuum, valve plate 101 falls to the spider 109 and the milk in valve chamber 102 flows through cut-outs 110 in the spider into the milk receiving container 61.

50 55 The valve retaining ring and valve chamber may be readily removed from cover 63 by loosening ring nut 66 which maintains the yoke 65 in contact with the shoulder 116 of the valve chamber. The valve chamber may then be lifted from the retaining ring and the retaining ring may be lifted from the opening 107 in cover 63. The valve plate and spider may be removed from the valve retaining ring. The complete and simple disassembling of the elements of the valve matter permits each element to be properly and thoroughly cleaned.

60 65 70 75 80 85 90 95 The valve retaining ring illustrated in Figs. 9 and 10 comprises a tubular sleeve 120 having an outwardly projecting flange 121. The sleeve is adapted to be positioned in opening 107 in cover 63, the outwardly projecting flange 121 being disposed on the upwardly extending rim 108 which defines opening 107. Sleeve 120 is provided with an internal ledge 122 and a cross bar 123. The cross bar is preferably formed with a raised central section 124 having an aperture 125 located centrally with respect to the sleeve. Valve plate 101 having a centrally positioned depending guide pin 113 is positioned on the cross bar 123, aperture 125 receiving guide pin 113. The guide pin and aperture cooperate to maintain valve plate 101 in centered position at all times. The enlarged base portion 115 of valve chamber 102 fits loosely within sleeve 120 and is positioned on ledge 122. The valve re-

taining ring and valve chamber are maintained in assembled relation and the assembly is maintained in opening 107 in cover 63 by means of yoke 65, the extremities of the yoke bearing upon shoulder 116 of the valve chamber.

Air spigot 118 communicates with the interior of valve chamber 102 and with a vacuum pump. Milk spigot 119 connects with the interior of the valve chamber and with the teat cups. The operation of the valve, removal, and disassembling of the elements are similar to that described in connection with the elements of Figs. 7 and 8.

The valve retaining ring illustrated in Figs. 11 and 12 may be formed by a stamping operation. Sleeve 126 is drawn from sheet metal and is provided with an outwardly flared rim 127. The sleeve is adapted to be positioned in opening 107 in cover 63, the outwardly flared rim 127 being disposed on upwardly projecting rim 108 which defines opening 107. The sleeve is formed with an integral cross member 128. The central portion of the cross member is preferably raised as at 129. The raised central portion of the cross member is provided with an aperture 130 which is centered with respect to the sleeve. Valve plate 101 having a centrally positioned depending guide pin 113 is positioned on cross member 128, the aperture 130 receiving guide pin 113 whereby the valve is maintained in centered position at all times. In forming the aperture 130 and the raised central portion of cross member 128, the metal is preferably drawn to provide a bearing surface for pin 113 which is longer than the normal thickness of the cross member.

Valve chamber 131 is provided with an outwardly projecting flange 132 adjacent its base. The base portion of the valve chamber is adapted to be positioned within sleeve 126, the lower surface of flange 132 contacting the outwardly flared rim 127 of sleeve 126. The lower end of the inner wall of valve chamber 131 is ground to form a valve seat 133. The valve retaining ring and the valve chamber are maintained in assembled relation and the valve retaining ring is maintained in opening 107 by means of yoke 65. The extremities of the yoke bear upon the upper surface of flange 132 of the valve chamber.

The air spigot 134 communicates with the interior of the valve chamber and with a vacuum pump. Milk spigot 135 communicates with the interior of the valve chamber and with the teat cups. The operation of the valve, removal, and disassembling of the elements are similar to that discussed in connection with the structure illustrated in Figs. 7 and 8.

It is apparent that a valve chamber and valve member are provided for each of the vacuum pumps. For a single milk container, the cover for the container is provided with two valve members, each valve member being connected to its respective vacuum pump. If desired, a trap may be provided between each of the valve members and vacuum pumps.

In the operation of the milking machine, studs 25 are adjusted to produce the desired degree of vacuum developed by the vacuum pumps. Oil cups 35 are filled with lubricating oil, and if desired, a small amount of lubricating oil may be placed in wells 5 of base 1. As cranks 48 are rotated, connecting rods 47 reciprocate the tubular members 38 on guide rods 36. The connection between cranks 48 and connecting rods 75

47 will be lubricated since the connecting pins will dip into the oil wells 5 at each revolution of the cranks.

As tubular members 38 reach their lowermost positions on guide rods 36, the lower ends of the tubular members dip into the oil in oil cup 35. The tubular members 38 fit loosely over guide rods 36 to provide a fair amount of clearance between the tubular member and the guide rod. Sufficient oil is retained between the guide rods and the lower end of the tubular members by capillary action, and because of the surface tension of the oil, a film of oil is carried along the guide rods as the tubular members are reciprocated upwardly. The guide rods and tubular members are thereby thoroughly lubricated. If the guide rod and tubular member are thoroughly cleaned, it will be found that after several revolutions of the crank and several full strokes of the tubular members along the guide rods, a film of oil will have been carried along the guide rods and along the entire length of the stroke of the tubular member.

In operation, the oil which is carried along the guide rod also passes through aperture 45 in tubular member 38 and drill holes 46 in collar 43 and pin 44 and lubricates the connection between pin 44 and the upper end of connecting rod 47. After some operation of the machine, it will be found that sufficient oil has been carried along the guide rod and has passed through aperture 45 and drill holes 46 so that a small amount of oil passes downwardly over connecting rod 47 to lubricate the connection between crank 48 and connecting rod 47.

Although I have illustrated a particular form of milking machine it is apparent that various elements may be embodied in other forms of machines and apparatus without departing from the spirit of my invention.

It is to be understood that the foregoing description is merely illustrative of my invention and that various modifications may be made without departing from the scope of my invention.

For example, I have illustrated the valve plate 101 as being dome-shaped and drawn or formed from sheet metal and the guide pin 113 as being secured to the valve plate by riveting. It is apparent that the guide pin may be secured to the valve plate by screw means with equal effectiveness, or the valve plate may be cast with the guide pin cast integral with the plate. Further modifications will present themselves to those skilled in the art.

I claim:

1. In a device of the class described, a vacuum pump, comprising a cylinder having a pair of diametrically opposite apertures therein and a piston mounted reciprocably in said cylinder, and adjustable means for centering said cylinder with respect to said piston and sealing said apertures.

2. In a device of the class described, a vacuum pump comprising a cylinder having a pair of diametrically opposite apertures therein, a piston mounted reciprocably in said cylinder, and an adjustable clamping ring encompassing said cylinder and adapted to seal said apertures and to center said cylinder with respect to said piston.

3. In a device of the class described including a substantially vertical panel and a cover plate, a vacuum pump comprising a cylinder having diametrically opposite apertures therein supported from said cover plate and a piston mounted reciprocably in said cylinder, and an adjust-

able clamping ring secured to said vertical panel and encompassing said cylinder, said clamping ring being adapted to seal said apertures and to center said cylinder with respect to said piston.

4. In a device of the class described including a substantially vertical panel and a cover plate, a vacuum pump comprising a substantially vertical cylinder supported from said cover plate and having apertures therein, a piston secured to a piston rod and mounted reciprocably in said cylinder, adjustable means for centering said cylinder with respect to said piston and sealing said apertures, and means for reciprocating said piston in said cylinder comprising a substantially vertical guide rod, a tubular member mounted slidably on said guide rod, said piston rod being operatively connected to said guide rod, and means for reciprocating said tubular member on said guide rod.

5. In a device of the class described including a substantially vertical panel and a cover plate, a vacuum pump comprising a cylinder having a pair of diametrically opposite apertures in the walls of said cylinder, said cylinder supported from said cover plate and a piston mounted reciprocably in said cylinder, and means for centering said cylinder with respect to said piston

and adjusting the vacuum developed by said pump comprising an arcuate clamping ring having outwardly projecting end portions, one of said end portions being fixedly secured to said panel, and a threaded stud adapted to draw the free end portion toward the fixed end portion and draw said ring about said cylinder to center said cylinder and seal said apertures.

6. In a device of the class described, a vacuum pump comprising a substantially vertically positioned cylinder having at least two opposite apertures therein, a piston secured to a piston rod and mounted reciprocably in said cylinder, adjustable means for centering said cylinder with respect to said piston and for sealing said apertures to adjust the vacuum developed by said pump, a substantially vertical guide rod, a cup adapted to contain a lubricant positioned at the lowermost end of said guide rod, a tubular member mounted slidably on said guide rod and rigidly connected to said piston rod, and means for reciprocating said tubular member on said guide rod, the lower end of said tubular member extending into said cup in the lowermost position of said tubular member.

BENJAMIN H. ANDERSON.
